UNITED STATES PATENT OFFICE.

ALBERT L. MILLER, OF NEW YORK, N. Y.

CAR-COUPING.

SPECIFICATION forming part of Letters Patent No. 249,782, dated November 22, 1881.

Application filed May 27, 1878.

To all whom it may concern:

Be it known that I, ALBERT L. MILLER, of the city, county, and State of New York, have invented certain Improvements in Car-Couplings, of which the following is a specification.

This invention is designed more particularly for use on "elevated railroads," so called, in cities, in the working of which, owing to the short radius of the curves, the ordinary car-coupling is inadmissible, and in which the use of a single and continuous metal bar pivoted at its opposite ends underneath the bodies of two adjoining cars has been, previous to my invention, the only known feasible means of coupling the cars on such railroads. This device, however, involved the frequent and dangerous necessity on the part of the attendant or operative of passing beneath the cars to couple or uncouple the latter.

20 My invention is designed to obviate such drawbacks; and to this end it comprises certain novel combinations of parts, whereby said object is secured.

Figure 1 is an inverted plan view, and Fig. 2 a longitudinal vertical sectional view, of a car-coupling made according to my said invention; and Fig. 3 is a front view, more clearly representing one portion thereof.

A A indicate the platforms of two adjoining cars to be coupled, and B is a transverse beam provided at or on the under side of each car-body. On each beam B is a skeleton bracket, a, which sustains a longitudinally-sliding buffer-bolt, C, pressed outward by a suitable spring, b. On the outer end of each buffer-bolt C are lugs c, directly under the platform, between which is passed the inner end of a long draw-head bar, D, and which is pivoted in said lugs by means of a removable pin, d. An opening, e, is provided in each platform to afford access to the pin d when occasion requires. Upon the outer end of each draw-head bar D is provided a draw-head, D'. These draw-heads may be of the ordinary variety, fitted for use with a simple link and pin, or they may be constructed, as shown in the drawings, for automatic coupling, a link, f, being held at each end in the adjoining draw-heads by a pawl, g, the latter actuated to release the link by a suit-

able lever, h, provided on the end of the pivot 50 of each pawl. Each draw-head rests upon a horizontal suspension-bracket, F, attached to the under side of the front portion of each platform, and of such length as to admit of the requisite lateral swing of the draw-head. 55

It will be seen from the foregoing that the draw-heads, instead of being kept rigidly in line with the length of the cars to which they are respectively affixed, are permitted a lateral motion proportioned to the angle to which, with 60 reference to each other, the two adjoining cars are brought while passing a curve of small radius, at the same time that the two connected draw-heads may be uncoupled and recoupled with quite as much ease and convenience as 65 any ordinary coupling.

In order that the two draw-heads on a straight track may be caused to come (nearly or quite automatically) opposite each other for coupling, each suspension-bracket has a recess, m, 70 at its central part, which tends to retain the draw-head therein unless or until a positive force is applied to turn it laterally in one direction or the other; and as the draw-heads, in practice, are generally uncoupled on a straight 75 track, the draw-head is left and retained in place for most convenient recoupling. The ends a" of the recess m should be sloping, as shown in Fig. 3, in order to enable the draw-head to pass therefrom when actuated by positive force, as aforesaid. 80

What I claim is—

The car-coupling consisting of the car-body having the beam B, provided with bracket a, the springing buffer-bolt C, passing through 85 said bracket and beam, and provided on its outer end with lugs c, the draw-bar D, pivoted in said lugs by means of the removable pin d, the outer end of the draw-bar having the draw-head D', resting in the bracket F, and having 90 a lateral movement therein, and the opening e in the platform A, to operate the pin d, as shown and described.

ALBERT L. MILLER.
